UNITED STATES PATENT OFFICE.

ALBERT T. WALRAVEN, OF DALLAS, TEXAS.

GUMMING MACHINE.

Application filed October 18, 1921. Serial No. 508,459.

To all whom it may concern:

Be it known that I, ALBERT T. WALRAVEN, a citizen of the United States, residing at Dallas, in the county of Dallas and State of Texas, have invented certain new and useful Improvements in Gumming Machines, of which the following is a specification.

This invention relates to new and useful improvements in gumming machines.

10 The object of the invention is to provide a machine for applying glue to certain portions of sheets which are fed into said machine. A further object of the invention is to apply the glue to restricted portions in a rapid and efficient manner. Another object of the invention is to convey the sheets thru the machine for a period of time before discharging the same in order to give the glue an opportunity to dry, and thus prevent the sheets from sticking to each other when they are discharged in a pile. A further object is to provide means for automatically coating presser feet with glue which is imprinted upon the sheets.

25 In carrying out the invention a glue applying device is supported above a conveyor belt on which the sheets are carried. A fountain is provided and means is interposed, for applying the glue from the fountain to the said device. Other conveyors are associated with the main conveyor for carrying the wet sheet thru circuitous path so as to give it an opportunity to dry before it is discharged.

30 A construction designed to carry out the invention will be hereinafter described together with other features of the invention.

The invention will be more readily understood from a reading of the specification and by reference to the accompanying drawings, in which an example of the invention is shown and wherein:

Fig. 1 is a plan view of a machine constructed in accordance with my invention,

45 Fig. 2 is a longitudinal vertical sectional view of the same,

Fig. 3 is an enlarged longitudinal sectional view of the upper portion of the machine,

50 Fig. 4 is an elevation of the feeding gate,

Fig. 5 is a detail of one of the take-up devices for the presser foot cylinder,

Fig. 6 is a detail of the gate,

Fig. 7 is a plan view of a sheet having portions coated with glue and illustrating the sheets which are gummed by this machine,

Fig. 8 is an enlarged cross section of the roller driving means,

Fig. 9 is a vertical sectional detail on the line 9—9 of Fig. 8, and

Fig. 10 is an enlarged longitudinal sectional view on the line 10—10 of Fig. 1.

In the drawings the numeral 10 designates an elongated base which may be suitably constructed and fastened together. On opposite sides near the front end of the base upright standards 11 are mounted, while on opposite sides near the rear of the base similar upright standards 12 are secured. Intermediate standards 13 are also mounted on opposite sides and between the standards 11 and 13 other intermediate standards 14 are mounted on opposite sides. Longitudinal side bars 15 extend from the standard 11 to the standard 13 on each side and rest upon the standard 14. Similar bars 15' extend from the standard 13 to the standard 12 on each side of the machine and each bar 15' is aligned with the bar 15 on its side of the machine.

A driving roller 16 is mounted in the standards 11 between the bars 15, and supports the forward end of a conveyor belt 17 which is preferably made of fabric such as 85 duck or any other suitable material. The rear end of said belt is supported on a roller 18 mounted between the standards 12. The upper run of this belt is horizontal and substantially level with the top of the bars 90 15 and 15'. The lower run of the belt passes under a roller 19 mounted between the standards 14 and that portion of said belt which extends between the rollers 18 and 19 is inclined downwardly toward the latter roller.

The upper run of the belt is also supported on an intermediate roller 20 mounted between the standards 13. A roller 21 is mounted immediately above the roller 20, while a similar roller 22 is mounted immediately above the roller 16. Between the upper ends of the standards 11, a roller 23 is mounted, while a roller 24 is mounted between the upper ends of the standards 13. These rollers have circumferential grooves 100 25 to receive endless strings. The strings

2
are maintained in spaced relation by the grooves and it is to be understood that in the following description all rollers which support strings are likewise grooved and constructed.

A feeding table 26 is mounted on the standards 11 and projects forwardly from the same, said table being supported by braces 27. The upper surface of the table 10 is substantially level with the upper surface of the belt 17, and the rear edge of said table is shaped to overhang the front end of said belt. The sheet which is to be gummed is placed on this table and fed in between the 15 rollers 16 and 22. The strings 25 travel in such close proximity to the belt as to hold a sheet of paper flat and smooth upon the surface of said belt. In Fig. 7, I have shown a sheet A which this machine is adapted to 20 gum, but it is to be understood that the use of the machine is not to be limited to such a sheet. The sheet A has its corners cut off and at each corner is provided with a gum panel B. The particular sheet illustrated is 25 designed for a book cover protector and it is important that the glue be imprinted on restricted portions thereof.

On each bar 15 I mount a take-up device 28 in which a sliding bearing box 29 is 30 mounted and depressed by a coiled spring 30. The boxes 29 support the ends of a shaft 31 extending transversely of the machine. On this shaft is mounted a cylinder 32. At each 35 end the cylinder is provided with radially projecting presser feet 33. The face of each foot is shaped to imprint one of the panels B. The feet are arranged in pairs, a pair projecting from each side of the cylinder. Each foot of a pair is spaced from the 40 other so as to properly imprint the panels B, at the end of the sheet A. Arranging two pairs of presser feet at each end of the cylinder, two sheets may be imprinted at each revolution of the cylinder.

45 In rear of each take-up 28 I mount on the bar 15 an upright bracket 34. Each bracket has a hanger 35 on its inner side and a glue reservoir or tank 36 is supported in these hangers. The tank has its forward end 37 50 inclined toward the presser feet and terminating at a lower elevation than the upper edge of the tank. Arms 38 have their rear ends pivoted to the upper ends of the brackets 34 and extend forwardly. A brush 55 cylinder 39 is journaled between the forward ends of said arms and is suspended over the edge of the front 37. The brush cylinder has bristles only at its ends so as to wipe the faces of the feet 33, and not to pick up unnecessary glue. As shown best in Fig. 3, 60 flat springs 40 secured to the brackets bear upon the arms 38 so as to force the brush cylinder down into contact with the presser feet and also to cause it to dip into the tank 65 to pick up the glue. As the presser foot

cylinder is revolved the brush cylinder will be revolved by a belt 80 running over pulleys 81 and 82 respectively mounted on the shaft 31 and the shaft of the brush.

In order that the sheets A, may be properly fed under the presser feet, I mount a swinging gate 41 on a shaft 42 supported in bearing boxes 43 on the bars 15 adjacent the rollers 16 and 22. This gate has its lower edge provided with notches 44 thru which 75 the strings 25 may pass and whereby the lower edge of said gate may swing into close relation with the belt 17 and prevent the passage of a sheet until said gate is swung rearwardly. The gate is placed at such a 80 distance from the cylinder 32 as to cause the sheet to properly ride under the presser feet 33, when said sheet is released.

For driving the parts I provide a pulley 45 which is driven by a belt 46 from any 85 suitable source. The pulley 45 is mounted on a shaft 45' (Fig. 8) on which a gear wheel 47 and a gear 48 are also mounted on opposite sides of the bar 15. Referring to Fig. 3, the gear wheel 47 is driven in a counter clock-wise direction. The gear 48 meshes with a pinion 48' mounted on the shaft of the roller 16. A pulley 83 on the shaft of the roller 16 drives a pulley 84 on the shaft of the roller 22 by a belt 85. By 90 this arrangement the co-acting portions of the belt 17 and the strings 25 are caused to travel rearwardly. The gear 47 also meshes with a gear 49 which in turn drives idler gears 50 and 50' all of these gears being 95 suitably mounted on the bar 15. The gear 50' drives a larger gear 51 which is mounted on the shaft 31 of the presser foot cylinder. The arrows in Fig. 3, indicate the direction 100 of revolution of the gears and it will be seen that the presser foot cylinder is properly 105 revolved to pass over the sheet A. It is to be understood that various means for driving the parts may be employed and the invention is not to be limited to the 110 structure illustrated and described.

For swinging the gate I mount an arm 52 on the same just inside of the bar 15 so as to rest upon a cam 53 which is mounted on the shaft 54 on which the gear 50 is mounted. 115 This gear meshes with and is driven by the idler 49. Each time the cam revolves the gate is swung down to permit the passing of a sheet and the gears are timed so that the gate will be swung twice to each 120 revolution of the gear 51 which revolves the cylinder 32. After the sheet is carried rearwardly on the belt 17 to the end of the latter. It is obvious that the glue which 125 has been imprinted upon the sheet will be wet and, therefore, if the sheet was immediately delivered from the machine, the next sheet delivered would stick thereto. It is necessary for the sheet to remain in the ma- 130

chine until the glue is dried and this is accomplished by conveying the said sheet back and forth thru the frame until it is dry.

- 5 Between the upper ends of the standards 12 I mount a string roller 55, while below the roller 18, I mount another string roller 56. Between the standards 11, a string roller 57 is mounted. Endless strings 58 have one end supported on the roller 55 and the 10 other end on the roller 57. The upper run of the string pass around and under the end of the belt 17, which is supported on the roller 18, while the under run of the strings are carried around and under the roller 56. 15 The upper run of the strings 58 are supported on intermediate rollers 59 mounted between the standards 13 and 14. The sheet upon reaching the rear of the belt 17, is carried between the strings and the belt and 20 passes under the roller 18. The strings 58 support the sheets and carry it forwardly and downwardly to the front of the frame. The strings diverge from the bottom run of the belt 17 so as to free the sheet therefrom. 25 A second string conveyor is mounted below the first and a canvas belt or conveyor 59 is interposed therebetween. The conveyor 59 has its forward end passing over a roller 60 mounted above the roller 57, 30 while its rear end is supported on a roller 61 mounted between the standards 12. The upper run of the conveyor 59 passes under the roller 57 and thus received the sheet A therefrom. The upper run of said conveyor 35 is supported on rollers 62 mounted between the standards 13 & 14. The lower run of the belt 59 passes over a roller 63 below the roller 57. The conveyor 59 carries the sheet A rearwardly and delivers it to the 40 strings 64 of the second string conveyor. This string conveyor has its rear end supported on a roller 65 above the roller 61 and its forward end supported on a roller 66 mounted between the standards 11. The 45 strings pass under the rear end of the conveyor 59 and diverge from the same. The strings are supported on rollers 67 mounted between the standards 13 and 14. A fabric conveyor 68 has its forward end supported 50 on a roller 69 above the roller 66, while its rear end is supported on a roller 70 mounted between the standards 13. The upper run of the conveyor 68 passes under the roller 66, and is supported on a roller 71 mounted between the standards 14. The lower run of said conveyor passes around a roller 72 below the roller 66. When a sheet is delivered to the conveyor 68 it is carried rearwardly and enters between a pair of endless belts 73 and 74, from which it is discharged into a tray 75. The belts 73 and 74 are suitably driven and the details of the same are unessential as they form no part of the invention. 60 65 It will be noted that the conveyors and

the strings diverge from each other so that when a sheet is delivered from one to the other it is freed from the one from which it has been delivered. The sheet will be carried back and forth thru the same several times before being delivered and under ordinary conditions should be dry when discharged. However, if necessary artificial heating means could be employed.

In operating the machine the operator 75 places the sheet A upon the table 26 and slides its forward edge in between the strings 25 and the belt conveyor 17. The sheet is carried rearwardly until it contacts with the gate 41. The gate 41 arrests 80 the sheet and at the proper time is swung so as to release the sheet. This is necessary in order that the forward edge of said sheet may arrive under the cylinder 32 at the proper time for the advancing presser foot on each side thereof to register with the forward edge of said sheet and properly imprint the same as it is carried under said cylinder. The presser feet are supplied 85 with glue by the brush 39. The sheet is conveyed rearwardly and passes around the roller 18 onto the strings 58 from which it is conveyed back and forth thru the same over the conveyors 59, 64 and 68, until it is discharged between the conveyors 73 and 90 74 at which time it will be dry and ready for use.

It is obvious that various changes in the construction and arrangement of the parts may be made without departing from the 100 spirit of the invention.

What I claim, is:

1. In a gumming machine, a support, an endless belt mounted on the support, retaining means disposed over the belt and 105 moving therewith, a revolving imprinting device mounted immediately over the belt, means for supplying said device with glue, and a plurality of diverging conveyors receiving the work in sequence after it passes 110 from the belt.

2. In a machine for gumming book cover sheets, a support, a cylinder mounted on the support, an endless belt passing under the cylinder, a plurality of radial presser feet 115 carried by the cylinder at each end and co-acting with the belt, a glue receptacle adjacent the cylinder, a glue applying roller dipping in the receptacle and engaged by the presser feet, retaining means disposed immediately over and moving with the belt and under the cylinder, said retaining means traveling between the presser feet at the opposite ends of the cylinder, and means for imparting motion to the belt, retaining 120 means, and roller.

3. In a machine for gumming book cover sheets at the four corners only, a support, a revoluble cylinder mounted on the support, radial presser feet projecting from the 130

cylinder in position to imprint the corners only, of a book cover sheet, an endless belt for passing the sheet under said feet, means for applying glue to said feet, and retaining means moving with the belt for holding the sheet on the belt.

4. In a book cover gumming machine, a supporting frame, rollers mounted at opposite ends of the frame, an endless belt having its ends supported on the rollers, a revoluble cylinder mounted on the frame over the belt, a glue receptacle mounted over the belt, presser feet extending radially from the ends of the cylinder, retaining means passing under the central portion of the cylinder and free from the feet, a roller dipping in the glue receptacle, and means for imparting motion to the cylinder, belt, retaining means and roller.

5. In a book cover gumming machine, a supporting frame, rollers mounted at opposite ends of the frame, an endless belt having its ends supported on the rollers, a revoluble cylinder mounted on the frame over the belt, a glue receptacle mounted over the belt, presser feet extending radially from the ends of the cylinder, retaining means passing under the central portion of the cylinder and free from the feet, a roller dipping in the glue receptacle, means for imparting motion to the cylinder, belt, retaining means and roller, a gate swinging over the belt and thru which the retaining means passes, and means co-acting with the cylinder for swinging the gate.

In testimony whereof I affix my signature.

ALBERT T. WALRAVEN.
